POST HOLE AUGER

Fred Thomas Smith, Kansas City, Mo., assignor to Precision Research and Development Company, Kansas City, Mo., a corporation of Missouri

Application April 1, 1955, Serial No. 498,668

3 Claims. (Cl. 255—19)

The present invention relates in general to devices for drilling holes in the earth and it deals more particularly with a portable auger for drilling post holes.

The object of the invention, broadly speaking, is to provide an improved post hole auger adapted to be mounted on and carried by a conventional farm tractor as an attachment thereto, all power required for operation of the auger being supplied by the tractor and all manipulation thereof being effected through the agency of control apparatus which is a standard part of the tractor.

Another object is to provide a post hole auger attachment of the character indicated which is economical to manufacture, which is sturdy in construction so as to be long-lived and trouble-free in use, which is easy to mount on the tractor and simple to service and maintain. In this connection a feature resides in the provision of an auger frame which is strong and so constructed as to resist accidental damage as well as injury such as otherwise might result through occasional mishandling by unskilled operators.

Still another object is to provide a tractor mounted post hole auger, which by virtue of its novel construction, permits drilling holes in the ground at locations very close to above ground obstructions such as buildings and trees. A further object resides in the provision of means insuring that the hole will, in every case, be drilled vertically.

Yet another object is to provide a post hole auger having a replaceable auger tip of improved construction and vastly superior operating characteristics.

Other and further objects of the invention, together with the features of novelty whereby the objects are achieved, will appear in the course of the following description.

In the drawings which form a part of the specification and are to be read in conjunction therewith, and in which like reference numerals indicate like parts in the various views:

Fig. 1 is a perspective view showing my post hole auger mounted on the rear end of a conventional farm tractor;

Fig. 2 is a fragmentary side elevational view of the auger showing the parts thereof approximately in the position they occupy when the auger tip rests on the surface of the ground preparatory to drilling a hole therein;

Fig. 3 is an enlarged perspective view showing the assembly of parts at the upper end of my auger; and

Fig. 4 is an enlarged cross-sectional view taken along the line 4—4 of Fig. 1 in the direction of the arrows.

My auger employs a rigid generally U-shaped frame comprising a pair of laterally spaced arms 10, 11 and a yoke 12 connecting the arms at their rear ends. Preferably formed from heavy steel plate bent to the shape shown in the drawings, the yoke has a transverse web portion 12a, a pair of parallel legs or side portions 12b extending forwardly from the web and a pair of ears 12c extending outwardly from the respective side portions; as will be clear from Fig. 2, the line of intersection

2

between each ear and its associated side portion 12b is inclined at an angle of approximately 45° to the plane of the web 12a.

Arms 10 and 11 conveniently are made of steel pipe, each being welded at 10a to the forward face of one of the ears 12c on the yoke. The arms thus extend forwardly from the yoke in slightly diverging fashion. At its forward extremity, each is flattened and pivotally connected to the rear axle housing 14 of the tractor, this being accomplished by means of a clamping bracket 15 mounted on the axle housing and a pivot bolt 16 connecting the arm to the bracket. So mounted, it will be understood that the U-shaped auger frame extends rearwardly from the tractor and is symmetrical about the center line of the tractor. Its rear end (i.e., yoke 12) is of course swingable up and down about the horizontal axis defined by pivot 16.

Raising and lowering of the auger frame is effected by the tractor lift arms 18. The two arms are standard apparatus on tractors, and the manner in which they are controlled by the operator is well known to those versed in the art. Accordingly it will suffice here simply to say that the lift arms are hinged to the rear of the tractor for up and down movement and can be raised 20 or lowered at will through suitable linkage powered by the tractor hydraulic system. Hydraulic connection arms 18a are pivotally connected to the lift arms 18 intermediate of the connections thereof to the rear of the tractor and the rearwardly extending arms 10 and 11, the connections being made by removable pins 18b connected by chains 18c to the tractor itself. Arms 18a are pivoted at their other ends to hydraulic connection arms 18d which are operated from the conventional tractor hydraulic system. Thus, rotation of arms 18d around their 25 pivotal mounting to the hydraulic means will raise or lower arms 18a and thus raise or lower arms 18 which, in turn, raise or lower arms 10 and 11. By means of brackets 19, the rear ends of the respective arms are coupled to opposite sides of the auger frame at points 30 spaced rearwardly of the pivots 16, whereby upward or downward movement of arms 18 is transmitted to the auger frame to raise or lower the yoke 12.

Between the opposite sides of the yoke I provide a gear box 20 which is pivotally connected to the yoke by means of shoulder bolts 21; the latter extend through journal apertures in the respective side members 12b and have their ends received in internally threaded apertures in the side walls of the gear box. Bolts 21, in other words, serve as trunnions on which the gear box is 45 adapted to turn about a horizontal axis.

The gear box has a vertical shaft 22 journaled in its upper and lower walls. On this shaft my auger is hung, a thrust collar 22a being provided to carry the weight.

The auger shaft is a hollow tube 24 in whose upper end is received the downwardly projecting portion of shaft 22, the two being connected together by a coupling pin 23. A spiral flight auger blade 24a formed of sheet metal is secured to the exterior of the auger shaft as by welding; adjacent turns of this blade are uniformly spaced 55 along the length of the shaft but at the lower extremity of the shaft a one-turn auxiliary spiral blade 24b is interleaved with the final turn of spiral 24a. The lower terminus of blades 24a and 24b, in other words, are diametrically opposite one another at the lower end of shaft 24.

The triangular auger tip 25 is a tempered sheet metal member bent to form a pair of opposed scoops having sharpened outer edges 25a (see Fig. 4). The two scoops terminate at the top in bent-over flanges 25b, each adapted to seat on and be bolted to the lower extremity of one of the spiral flights 24a, 24b. Between the two flanges, tip 25 preferably has a short upstanding stub post (not shown) which is received in the lower end

of the hollow shaft 24 for aligning the two and strengthening the connection. A given auger tip can easily be replaced simply by removing bolts 26, withdrawing the tip from the auger flights, and bolting a fresh one thereon in its place.

The transverse curvature of the tip 25, which is of generally ogee character along all horizontal planes, is of course reinforced by the integral flanges 25b at the top where the circumferential forces are greatest during drilling; this construction being such as to give the tip great strength and rigidity. The length of the tip in a vertical direction preferably is of the same order as the outside diameter of the auger, so that the included angle between the upwardly diverging cutting edges 25a is an acute angle; the purpose of this will be clear presently.

Within the gear box 20 vertical shaft 22 is mounted by means of a pair of meshing bevel gears (not shown) to a horizontal shaft suitably journaled in and projecting through the front wall of the box; the projecting portion has secured thereto the yoke 27a of a universal joint 27 connecting same to a square shaft 28. When the auger is elevated as shown in the drawings, shaft 28 extends downwardly and forwardly from the gear box 20. Its forward portion is telescopingly received in a square tube 30 which in turn is coupled at its forward end by a similar universal joint 32 to the power take off of the tractor. The telescoping arrangement between the two members forms an extensible drive shaft between the two universal joints, and the universal joints on the other hand accommodate themselves to changes in the angular aspect of this drive shaft relative to the horizontal as the auger is raised or lowered.

As the auger moves downwardly into the ground in the course of drilling a hole, the yoke 12 swings in an arc about pivots 16, and the path of descent of trunnion bolts 21 therefore departs slightly from the vertical. To compensate for this and make it possible to obtain a vertical hole, it is desirable that the auger be inclined slightly from vertical at the beginning of drilling, the direction of inclination being such that the tip initially engages the ground at a point spaced rearwardly of a vertical line through the bolts 21 and the amount of this rearward displacement being approximately equal to the rearward component of the travel of bolts 21 in the course of their subsequent downward movement. Thus, referring to Fig. 2 where the auger tip may be assumed to be resting on the surface of the ground, the shaft 24 is shown inclined approximately 4° from vertical; it being understood that the proper angle will vary in accordance with the length of the auger, the distance of pivots 16 above the ground, the distance between pivots 16 and 21, etc.

To obtain this inclination, pivots 21 are so located with respect to the mass of the assembly supported on those pivots as to cause the auger shaft 24 to hang at a slight rearward angle. It is biased forwardly, however, by means of a coiled tension spring 34 having one end fastened to web 12a of the yoke 12, the other end of the spring being connected to an arm 36 which is secured to the side of gear box 12 by means of the pair of bolts 37. Stated differently, referring to Fig. 2, spring 34 produces a torque tending to turn the depending auger clockwise about pivot axis 21 while the weight of the auger and drive assembly suspended on that pivot produces a torque in the opposite direction, whereby a state of balance is obtained which holds the auger in the desired position. One of the bolts 37 extends through an elongated aperture 36a so that, when loosened, arm 36 can be turned about the other bolt 37, an arrangement which permits adjusting the angular aspect of arm 36 relative to the gear box. In this way the tension on spring 34 can be increased or decreased for the purpose of altering the angle at which shaft 24 will hang from pivots 21.

The manner in which my device is used should be

fairly evident from the foregoing description. In moving the tractor from place to place the auger naturally is carried in a sufficiently elevated position to clear the ground, and under this condition its hangs as a pendulum from the yoke 12, swinging movement thereof being snubbed however by the damping action of spring 34. The tractor can be driven forward, backward or turned in normal fashion and is halted with the auger over the place at which the hole is to be drilled. Then, by lowering the tractor, lift arms 18 (which the operator accomplishes by manipulation of the controls for the hydraulic system of the tractor) the auger is permitted to move downwardly until its tip rests on the ground. As previously pointed out, it automatically engages the ground at the proper angle to insure obtaining a vertical hole—say approximately 4° from vertical. The operator now places the power take off of the tractor in operation to turn the auger about its axis, the rotation thereof causing it to advance downwardly into the ground under its own weight. As it does so, the upper end moves rearwardly, straightening the auger to vertical and slightly stretching spring 34 in the course thereof.

Due to the improved design of the tip 25 it is possible in practice to drill a post hole of the usual depth in as little as five or six seconds, the total time naturally depending on the hardness of the soil, the rock content, etc. From the moment the tip of the auger is brought to rest on the ground until drilling of the hole has been completed, the pointed lower extremity serves as a positive live center for the auger, making the device self-centering throughout its rotation and eliminating all possibility of lateral shift or wobble. Chatter also is eliminated in drilling all soils except the most sticky clays. The steep relatively vertical angle of the cutting edges 25a minimizes the resistance which the earth offers to descent of the rotating auger, hence obviously is an important factor in achieving the aforementioned drilling speed; at the same time the scoop character of tip 25 peels earth from each cutting edge and delivers it in thoroughly loosened condition to the spiral flights 24a, 24b for elevation to the surface of the ground.

The downward advance of the auger is halted of course when the hole has reached the desired depth, whereupon arms 18 are used to draw the auger from the hole and elevate it above the ground preparatory to driving the tractor to another location.

Referring to Fig. 2, it is important to note that by virtue of the manner in which yoke 12 is constructed it extends over, rather than around the rear of, the gear box 20. As a result, it is possible to use my auger in drilling holes very close to buildings, trees or other above-ground obstacles, since any obstacle which will clear the auger itself will also clear the parts of the assembly at the upper end of the auger. Stated differently, there is nothing extending rearwardly of the auger to require placing the auger farther from an above-ground object than the auger itself requires.

The construction of my yoke 12 also is important from the standpoint of the strength which it gives to the U-shaped auger frame extending rearwardly from the tractor axle. This can perhaps best be visualized by imagining that the auger is elevated above the ground and that one of the lift arms 18 accidentally becomes detached from the auger frame as may occasionally happen in practice, particularly where the apparatus is being used by a careless, unskilled or inattentive operator. Under such circumstances the entire weight of the auger is thrown on one side of its supporting frame, producing a torque which tends to twist the frame out of shape. The extraordinary strain imposed upon the yoke at such times makes its strength very important, and the design of the yoke permits limited flexure of the flat parts thereof without taking a permanent set, so that even such an accident will result in no permanent injury to the parts. Also, because of its design, arms 10 are perfectly

straight members, making it possible to use high-strength steel tube for these parts.

From the foregoing it will be seen that my invention is one well adapted to attain all of the ends and objects hereinbefore set forth together with other advantages which are inherent to the apparatus.

It is to be understood that certain features and subcombinations are of utility and may be used without reference to other features and subcombinations. This is contemplated by and is within the scope of the appended claims.

Inasmuch as various embodiments of the invention may be made without departing from the scope thereof, it is to be understood that all matter herein set forth or shown in the accompanying drawings is to be interpreted as illustrative and not in a limiting sense.

Having thus described my invention, I claim:

1. In apparatus of the character described, a frame carried on the rear of a tractor for up and down swinging movement, said frame comprising a pair of laterally spaced substantially coplanar arms having their forward ends pivoted to the tractor, a U-shaped yoke connecting the rear ends of said arms, said yoke having a pair of opposed leg portions inclined upwardly and rearwardly from the respective arms and a bight portion spanning the space between the upper extremities of said legs, a gear box between the opposite leg portions of said yoke and below the bight portion pivotally supported on said leg portions to turn about a substantially horizontal axis said gear box having a power input shaft and a power output shaft operatively connected thereto, an auger carried by said output shaft in depending relationship to said gear box, means for turning said input shaft thereby to rotate said auger, said auger and gear box forming an integral pivotal assembly, said integral pivotal assembly so mounted and supported on said leg portions that the distribution of mass thereof causes the auger shaft to hang at a slightly rearward angle from the vertical, and a biasing spring operatively connected to said yoke and said gear box to yieldably resist the tilting of the auger shaft 40

and gear box so the former hangs at a lesser rearward angle than it would unrestrained.

2. Apparatus as in claim 1, having adjustment means for varying the biasing tension of said spring.

3. In apparatus of the character described, a frame carried on the rear of a tractor for up and down swinging movement, said frame comprising a pair of laterally spaced coplanar arms having their forward ends pivoted to the tractor, a yoke at the rear ends of said arms and spanning the space therebetween, said yoke comprising a U-shaped channel member with integral inclined ears projecting laterally from opposite legs thereof and abutting the rearmost extremities of the respective arms, a weld securing the rearmost end of each arm to the abutting ear whereby the frame formed by said yoke and arms is a rigid unitary assembly, said yoke having a pair of opposed leg portions inclined upwardly and rearwardly from the respective ears and a bight portion spanning the space between the upper extremities of said legs, a gear box between the opposite leg portions of said yoke and below the bight portion pivotally supported on said leg portions to turn about a substantially horizontal axis, said gear box having a power input shaft and a power output shaft operatively connected thereto, an auger carried by said output shaft in depending relationship to said gear box, and means for turning said input shaft thereby to rotate said auger.
